COMBINATION BOLL-BREAKER AND SPREADER-ROLLER

Richard M. Shelburne, Sherman, Tex., assignor to Hardwicke-Etter Company, Sherman, Tex., a corporation of Texas

Filed May 20, 1963, Ser. No. 281,688
4 Claims. (Cl. 19—38)

The present invention relates to apparatus for increasing the effectiveness of the various units of equipment in a cotton ginning system. The novel equipment described herein is referred to as a combination boll breaker and spreader roller, because it will function to improve, for subsequent operations in the system, the condition of cotton containing unopened or partially opened bolls, as well as cotton stalk in the form of long sticks. Accordingly, the apparatus is of particular usefulness as the first unit of machinery in a ginning system, in that the operations of all of the subsequent processing machinery are improved. However, it will be obvious that the novel equipment described herein, may be usefully employed at other positions in the ginning system, particularly where it is desired to spread out the cotton entering a unit, from the conventional cylindrical conveying conduits which are employed in ginning systems. As indicated, the equipment described herein is particularly useful in first acting upon machine-stripped cotton which, due to the modern methods employed to collect same, often contains quantities of unopened bolls etc., which need to be opened in order to expose the locks of cotton to the processing machinery, and in order to avoid losing these locks of cotton in the form of waste.

In addition to spreading the cotton, as mentioned, the equipment described herein also breaks up wads of cotton, which result from a clinging together of the cotton, due to excessive moisture content. Such wads are particularly prevalent in machine-picked cotton, and if they are permitted to pass on into the various processing units in the ginning system, the result may be choking of the machinery and frequent breakdowns. Again, even if such cotton does pass through the system, it may be poorly ginned and the resulting rough lint appearance may cause severe price penalties on the market. The application of the apparatus described herein, as the first unit in the ginning system, will serve to eliminate these wads, whereby all of the other units will be able to perform more effectively.

The problem existing in the art, is at least partially related in Patent 2,681,474 to Steele of June 22, 1954, wherein a boll breaker apparatus is described having blades which are moving with the direction of cotton feed, the major part of the cotton being fed through the lower part of the machine, moving in the direction of movement of the blades. While the Steele patent is addressed to substantially the same problem, it does not provide the violent boll and stalk breaking functions of applicant's invention, which results from the rapid deceleration of the movement of the cotton, and a radical change in its direction of movement, nor does the Steele apparatus serve to spread the cotton out, for uniform entry into the next unit of the system, such as the separator, as is provided for in the use of applicant's equipment.

The need for the present invention is particularly acute under present day methods, where high capacities are being reached in ginning plants or systems with supercharge type suction fans being employed to pull a much higher vacuum and to induce a much greater volume of cotton into the separator of the system. When using a high vacuum, as in present day unloading systems at a cotton gin, the velocity of the material going through round pipe and into the separator is so great that it has

2

very little opportunity to spread out to the full width of the separator. As a result, the bulk of the cotton and other material may be concentrated in the center of the separator, and if a great volume of material is being fed, a choked condition will result. If the bulk of the cotton is fed into the middle of the separator, undue wear will be produced on both the screen and the vacuum flights in the separator. Again, the next unit in line, receiving cotton from the separator, will not be properly fed. It will be apparent from consideration of the present invention, that the rapid decreasing of the velocity of the incoming cotton, and the spreading of this material across the full width of the separator, will result in an increased capacity for the separator.

To accomplish the above purpose, I have provided a unit of equipment, which may be associated with other units of a ginning system, which has a housing with a rapidly rotating shaft therein and with beating and spreading blades arranged in a particular manner on the shaft, the inlet for the material being disposed in offset relation from the axis of the shaft and in such manner as to discharge the incoming material directly against the blades which are moving at high speed in the opposite direction. As a result of this arrangement, the delivered material, which is moving at high speed, has its movement rapidly decelerated and brought to a stop, and has its direction of movement radically altered, with the result that bolls and stalks are thoroughly broken up. At the same time, the inlet is designed to be of width substantially less than the width of the housing to which it leads, and this together with the arrangement of flights of blades on the shaft in the housing extending from the center in opposite spirals, serves to separate the cotton in its movement through the unit, and while it is being subjected to beating and chopping action from the blades, in order to condition the material for delivery to succeeding units in the system.

The equipment described herein is suitable for use in systems where the material is delivered into the system at a velocity as great as 4,000 to 5,000 feet per minute. The unit may be built in various lengths such as 50" to connect with a 50" separator, or 70" to connect with a 70" separator but it will be understood that the equipment described herein may be used in other places in a ginning system, where the cotton is being transferred from one machine or unit to another by round pipes by the use of high velocity air moving the material through the pipes. For instance, it may be used where the cotton is passing from a round pipe with heated air into a tower drier, or where it is passing from the tower drier to a round pipe, to a cleaner or to a stick and green leaf machine.

In addition to the Steele Patent 2,681,474, previously mentioned, applicant is, of course, aware of disclosures in the art of boll breakers and the like, for use in cotton handling systems, as typified by such patents as Munger, 1,311,907 and Kinne, 1,186,798.

According to the invention, a new and improved apparatus of the character described is provided for decreasing the velocity of the cotton being fed into the separator and efficiently distributing the cotton across the full width of the separator so that its capacity is greatly increased. Apparatus according to this invention is also operative to break the cotton which is particularly moist and tends to cling together to thereby enhance the ginning operation, in a notably improved manner. This apparatus is adapted to accommodate unopened and partially opened bolls and sticks so as to minimize waste and otherwise break the cotton as necessary for efficient ginning.

The apparatus according to this invention includes a housing particularly adapted to be mounted with its output adjacent the separator (usually the first station in a

ginning installation), the housing carrying a shaft having oppositely spiralled, radially extending flat plates, the direction of shaft rotation, the geometric position of the shaft relative to the inlet of the housing and the close positioning of the housing walls relative to the shaft serving to spread the cotton and otherwise prepare the same for efficient ginning.

The objects, advantages, and novel features of the present invention will become apparent in the specification and claims, taken in connection with the accompanying drawings.

In the drawings:

FIGURE 1 is an end elevation view of the apparatus according to this invention connected to a separator in a ginning installation.

FIGURE 2 is a side elevation view of the equipment looking inwardly from the left of FIGURE 1.

FIGURE 3 is an enlarged side elevation view, partially broken out, of the apparatus according to this invention.

FIGURE 4 is a partial transverse elevation view, with the casing partially broken away, looking inwardly from the outlet or discharge side of the casing of the boll-breaker and spreader-roller which is the subject of the invention.

FIGURE 5 is a detail view of the shaft and blade structure.

FIGURE 6 is an end view of the shaft and blade assembly, looking inwardly from the right end of FIGURE 5.

FIGURE 7 is a developed view showing the position of the blades on the shaft.

Referring now to the drawings, there is shown in diagrammatic fashion a conventional separator 10 which usually constitutes the first unit in a ginning system or installation, the separator 10 having the usual vacuum wheel 12 and high velocity air suction means 14. The separator 10 may be connected in a system which includes sequential apparatus for drying, cleaning, ginning, lint cleaning, condensing, tamping and finally pressing the ginned cotton. For instance, the separator 10 may be mounted over a steady flow bin, where sufficient material accumulates to provide an even feed for the remainder of the system, and as is well known in the art, hot air may be provided to carry the cotton forward through such as a tower dried, cleaner, stick or burr machine, dried, cleaner, distributor, gin battery, lint cleaners, lint flue, condenser, and thence to the trumper and press.

The separator 10 has an inlet duct as at 16 which is of generally rectangular configuration and extends across substantially the entire width of the machine, the axis of this inlet duct being disposed in a generally horizontal plane. There is provided a combination boll breaker and spreader generally indicated at 18 and a transition duct 20 which is adapted to deliver cotton from a conventional circular duct according to the principles of the present invention. The boll breaker and spreader 18 comprises a housing preferably of sheet metal construction and formed with an inlet opening 24 (FIG. 3), and an oppositely disposed outlet opening 26 connected as by a flange joint 28 to the inlet duct 16 of the separator 10. The width of the housing between its opposed end walls 30 and 32, as well as the configuration of the housing outlet 26 corresponds to the inlet duct 16 of the separator 10 for reasons to become evident.

The housing carries a spreader shaft 34 which is joined at its ends to the opposed end walls 30, 32 in sealed ball bearing units 36 carried by each end wall 30, 32, as shown for instance, in FIGURE 4. These sealed bearing units 36 are constructed to form an air-tight joint between the shaft 34 and the end walls 30, 32, using fiber washers 37 and collars 38. The shaft 34 between the end walls 30, 32 is of enlarged hexagonal cross-sectional configuration, providing flat surfaces 35 to which are welded the opposed blade sets 39a, 39b, as illustrated in FIGURE 5 and also in FIGURE 6. In this regard, the symmetric

center of the shaft 34 (between the walls 30, 32) carries the blades 39 in continuous, symmetric and oppositely spiralled relationship as will be understood from FIGURE 7, which is a developed pattern of the blades 39 along the hexagonal shaft surface. Each blade 39 is in the form of a flat, generally rectangular plate of a substantial width so that, in the developed form shown in FIGURE 7, substantially the entire developed surface of the spreader shaft 34 is embraced by an effective blade surface.

The spreader unit described in effect comprises an open type cylinder of about 16" diameter including $3\frac{1}{8}$ " x $1\frac{1}{4}$ " steel blades welded to the heavy shaft. The blades are welded on an angle and not in planes transverse to the axis of rotation of the cylinder. The blades are welded in a double spiral arrangement, starting at the center of the shaft, the flight of blades toward one end of the shaft being right-hand while the flight of blades toward the other end of the shaft is left-hand. By mounting the blades at an angle with respect to planes transverse to the axis of rotation of the shaft, they will strike the material entering their paths of rotation, and the material will be deflected by them to one side. Because the blades are spirally arranged, as material is deflected by one of the blades, it comes into contact with the next blade following, and will be further deflected from its normal path. By reason of the fact that one flight of blades deflects the material in one direction, and the other half deflects the material in the other direction, the material which enters the housing centrally thereof, is divided and spread out to the full length of the cylinder. This spreading out action can be controlled by the speed at which the cylinder is rotated.

Preferably, each blade 39 is joined by welding with its lower end coextensive with a flat part of the hexagonal shaft surface. Such a hexagonal shaft surface facilitates joining the blades by welding and otherwise provides a structurally sound arrangement capable of heavy duty over substantial periods of time. The opposite free end 40 of each blade 39 is inclined in a downward direction away from the direction of shaft rotation (clockwise as viewed in FIGURES 2 and 3), this angle A of inclination being about 15°. The extreme outer ends of the blades may turn in a circle which is as close as $5\frac{1}{8}$ " to the top and bottom portions of the surrounding casing.

The housing is constructed and arranged to receive this assembled spreader shaft 34 so that a minimum tolerance is provided between the upper ends of the blades and the adjacent interior surface of the housing. Thus, as shown in FIGURE 3, the bottom housing wall 40 is smoothly curved from the inlet opening 24, thence terminating with a flat surface 42 which smoothly extends to the housing outlet opening 26. Likewise, the upper part of the housing 44 adjacent the outlet opening 26 is curved with a concentric, close relationship to the ends of the blades 39. The remaining part of the housing is conveniently formed with right angled top and side plates 46, 48, respectively, all of these sheet metal parts being joined to one another by any suitable means such as flange bolt joints 50. The end walls 30, 32 of the housing are mounted at the opposite ends of the lower, upper and front peripheral walls 42, 46, 48 of the housing. The inlet opening 24 of the housing is substantially shorter than the length of the side plate 48 and preferably embraces one-half this distance in symmetric relationship with the end walls 30, 32, as shown in FIGURE 1. Thus, the inlet feed is central of the length of the shaft and housing.

The transition duct 20 is of generally frustro-conical configuration having a rectangular base end 52 connected to the inlet opening 24 by a flange-bolt joint 56, the opposite apex end of this transition duct 20 (FIGURE 2) being of the usual circular configuration 58 and adapted to be connected by any suitable means to a circular conveying duct (not shown).

According to one important feature of the present invention, the axis A_1 of the transition duct 20 and inlet opening 24 is positioned at right angles to and above the axis of the spreader shaft 34, this axis A_1 intersecting a vertical plane passing through the axis of the spreader shaft 34 at substantially right angles. Such arrangement allows the incoming cotton to receive the full effect of the entire upper part of the blades 39 when the shaft 34 is rotated in a clockwise direction as viewed in FIGURES 2 and 3. The advantage of this arrangement is two fold: the increased area of the transition duct serves to reduce the incoming velocity of the cotton entering the housing; and, the beater blades tend to reduce the horizontal component of velocity to substantially zero, while substantially reversing the direction of movement of the cotton and thereafter forcing the cotton downwardly towards the bottom housing wall 40. When this takes place, the oppositely spiralled configuration of the blade sets 39a, 39b distributes the cotton outwardly in an even pattern along the length of the housing and shaft so that when the cotton is discharged through the housing outlet 26 and into the separator 10, there is provided an even lateral distribution of cotton with the advantages previously described. A unique feature of the unit described, and which is most important to its proper functioning is the fact that the inlet opening 24 is located at the top of the unit, whereby the rapidly moving material is thrown against the rotation of the cylinder and its blades. That is, the center of the inlet opening is above the center of rotation of the shaft. The heavy blades on the shaft, with their spiral arrangement, serve to halt the tremendous speed of material as it enters, and any wads of cotton which may be present are broken up by the angular slicing action of the blades, while the material is spread along the full length of the shaft and housing. The speed of the cylinder in the housing, coupled with the velocity of movement of the material entering the housing, results in such impact that any unopened or partially opened bolls will be opened by the impact, and the chopping action of the blades will break up any long stalks that may be in the material which is delivered to the housing.

The shaft 34 is driven by an electric motor 60, this motor being mounted at either end of the machine on an L-shaped bracket 62 (FIGURE 3) which is, in turn, joined to the top of the housing via a vertical bracket 64 and an inverted channel-shaped bracket 66. The shaft 68 of the electric motor 60 transmits drive to the shaft 34 (aligned therewith) via pulley wheels 70, 72 carrying a flexible V-belt 74, or any other suitable drive may be provided.

While the operation of the instant apparatus is believed to be evident, the same will be summarized as follows: Incoming cotton passing through the transition duct 20 carried by air at a velocity in the order of 4000-5000 feet per minute is slowed down by the expanding size of the transition duct 20. The shaft 34 which is rotating at a speed on the order of 500-1000 revolutions per minute in a clockwise direction (as viewed in FIGURE 3) strikes this incoming cotton and reduces its velocity substantially to zero and radically changes its direction of travel. It is important to note that the right angular relationship between the path of incoming cotton relative to a vertical plane passing through the shaft 34 enables the horizontal component of velocity to be stopped and the cotton is sharply and forcibly spread apart along the width of the housing, deflecting along its underside due to the close tolerance with the adjacent housing wall 40, and is then forced outwardly through the housing outlet opening 26 and into the separator 10 across substantially the entire width of the housing. After the material leaves the spreader unit, it may be further spread by the action of the angularly disposed blades which tend to fan and force the cotton leaving the housing out to a greater spread length of the unit itself.

While the invention has been described as being particularly adapted for assembly with the cotton separator, it is capable of use at other stations in the ginning installation. For example, the boll breaker and spreader 18 can be assembled to feed cotton into the gins or to move the cotton into a tower drier, or to a stick and green leaf machine. Where the boll breaker and spreader of this invention is used in a ginning system, at any point, it will be understood that any suitable by-pass arrangement may be provided, as is known in the art, to cut the unit in or to cut it out of the system, depending upon the condition of the cotton and the need for the particular type of processing which is provided by the unit.

From the above description, it will be understood that this combination boll breaker and spreader unit will solve three of the major problems which are present in high capacity or gin systems today. First, it decreases the velocity of the material entering the separator, which is usually the first unit in a ginning system, and spreads it across the full width of the separator, thereby allowing the separator to handle a larger volume of material and at the same time, properly feed that material to the machine which follows the separator in the sequence of processing provided by the system. Second, it will break up wads of cotton that tend to cling together and which are prevalent today in machine-picked cotton and cotton which contains more than a normal amount of moisture. By breaking up these wads as they enter the first unit of a ginning system, the driers and other processing units that follow, can better perform the functions for which they are intended. Third, the apparatus of the invention serves to break up the long portions of cotton stalk which may be brought in with cotton which is machine-stripped, and it also tends to open up the unopened and partially opened bolls of cotton that are prevalent in large quantities in both machine-stripped and hand-snapped cottons.

From the foregoing descriptions of the various embodiments of this invention, it is evident that the objects of this invention, together with many practical advantages are successively achieved. While preferred embodiments of my invention have been described, numerous further modifications may be made without departing from the scope of this invention.

It is to be understood that all matters herein set forth or shown in the accompanying drawings are to be interpreted in an illustrative and not in a limiting sense.

What is claimed is:

1. Apparatus for breaking and spreading cotton comprising: a housing having opposed end walls mounted at the opposite ends of means defining upper, lower and front peripheral walls; a spreader shaft carried for rotation by said end walls; spreader blades mounted on and about said shaft in oppositely spiralled relationship from the center of said shaft relative to said end walls, said blades being of flat, generally rectangular construction and presenting a substantially continuous developed surface along said shaft between said housing end walls, said developed surface extending obliquely with respect to the longitudinal axis of said shaft due to said spiralled relationship, an elongated inlet means along the central region only of said front peripheral wall, a generally frustroconical transition duct joined to said inlet means; the axis of said transition duct and inlet means being transversely above the axis of said spreader shaft and generally perpendicular to a vertical plane passing through the axis of said spreader shaft; and an outlet duct defined between said housing upper and lower peripheral walls opposite from said front peripheral wall extending substantially the entire distance between said housing end walls; drive means operative to rotate said blades at high speed toward said inlet means during their upper path of travel, whereby cotton entering said housing via said transition duct is abruptly decelerated in its movement and has the direction of its travel radically changed and said blades are operative to spread the cotton across said

housing in a substantially even pattern for discharge via said outlet duct.

2. Apparatus defined in claim 1 wherein said spreader shaft is of polygonal configuration, and said flat blades are welded at their inner ends to consecutive surfaces of said polygonal shaft.

3. Apparatus as defined in claim 1, wherein said drive means includes an electric motor mounted on a bracket at one end of said housing, whereby said housing forms a compact unit with said drive means and motor.

4. Apparatus capable of breaking bolls and stalk and for spreading out cotton conveyed through a cylindrical conduit in a cotton ginning system, comprising an elongated housing closed at its ends and having means defining upper, lower and front peripheral walls extending between said ends, a rotary shaft extending through the central part of said housing, a plurality of spaced blades mounted on said shaft and of such length that their edges move in close proximity to said connected walls, said blades being arranged in two oppositely spiraled flights extending from the center of said shaft towards the ends thereof providing spiral paths for movement of the cotton from the center toward the opposite ends of said housing, said housing having a substantially rectangular inlet opening delivery with a transition union connected thereto, means for rotating said shaft and said blades at high speed in said housing, said inlet being of such size and position as to deliver cotton directly against and in a direction opposite to that of the movement of said blades,

5

10

15

20

25

whereby the cotton entering the casing has its movement suddenly stopped and reversed in direction and is violently beaten to thereby break any bolls or stalks and to condition the cotton for later operations in the ginning system, said inlet opening being of width substantially less than that of the housing and being positioned substantially centrally of the length thereof, whereby said flights of blades spread the cotton outwardly toward the ends of said casing, and means for delivering cotton to said inlet in a current of air which is moving at high speed, said housing having an elongated outlet which is of width substantially equal to the length of said housing whereby to deliver the spread out cotton to an elongated inlet of a separator or other unit of a ginning system.
